HANDLE FOR SCREW DRIVER OR THE LIKE

Leonard Garth Huxtable, New York, N.Y., assignor to
Millers Falls Company, Greenfield, Mass., a corpora-
tion of Massachusetts

Filed Dec. 3, 1962, Ser. No. 72,701

Term of patent 14 years

(Cl. D93—4)

FIG. 1 is a plan view of a handle for screw driver or
the like embodying my new design;

FIG. 2 is a rear end view thereof;

FIG. 3 is a front end view thereof; and

FIG. 4 is a section on line 4—4 of FIG. 1.

The screwdriver blade which is shown broken away
in part for indeterminate length is disclosed in broken
lines for illustrative purposes only.

I claim:

The ornamental design for a handle for screw driver

or the like, as shown and described.
